UNITED STATES PATENT OFFICE.

ARTHUR JAMES CUMNOCK, OF RYE, NEW YORK.

WEB-CUTTING MACHINE.

1,072,829.

Specification of Letters Patent.

Patented Sept. 9, 1913.

Application filed July 27, 1906. Serial No. 328,128.

To all whom it may concern:

Be it known that I, ARTHUR J. CUMNOCK, a citizen of the United States, and a resident of Rye, New York, have invented certain new and useful Improvements in Web-Cutting Machines, of which the following is a specification.

My invention relates to a web cutting machine, particularly adapted to cut a tubular web into pieces, which may of course be cut directly across the web, but which in practice are usually of broken contour to form parts of garments or similar articles.

15 In my Patent No. 829,098 granted August 21, 1906, I have shown a machine for cutting a tubular web, in which machine is provided a mandrel supported within the web for extending the same, said mandrel 20 being provided with cutting blades on its opposite surface for cooperating with movable cutting blades in the machine for severing the web. In my Patent No. 829,099, granted August 21, 1906, I have shown another tubular web cutting machine in which is also shown a mandrel supported entirely within the web for maintaining lateral tension therein. In both of these machines the opposite faces of the tubular web are 25 separately cut, the web being in its original folds, that is, with the selvages which unite the two plies of the web remaining in their original position.

My present invention has for its object 35 the folding of the web so as to bring these selvages on the faces of the web before the cutting operation, and preferably to bring such selvages in superposition, so that bilaterally symmetrical portions can be cut 40 from the web, the central line of which shall correspond with the median line of one of the faces of the fabric rather than with a selvage, both plies of the web being cut together.

45 Further objects of the invention will appear in the specification and be pointed out in the claims.

In the drawings, Figure 1 is an illustrative view showing the tubular articles re-folded into final form ready to be sewn together to form the finished article. Fig. 2 shows the web cut into tubular articles by the means provided in the present application. Fig. 3 is a side elevation of a ma-

chine embodying my invention, with a portion of the frame removed for clearness of illustration. Fig. 4 is a top plan view of the same. Fig. 5 is an end elevation of the same. Fig. 6 represents in perspective a mandrel detached from the machine, with a portion of the web ready to pass thereover. Fig. 7 is a similar view of a modified form of mandrel. Figs. 8, 9 and 10 are views corresponding to Figs. 3, 4 and 5 respectively of a modified form of my device.

Referring to Figs. 3, 4, 5 and 6 of the drawings, 11 designates the body of the machine, from which rise four corner uprights 12. Mounted on shafts 13 adjacent the upper ends of the uprights 12 are grooved pulleys 14 adapted to support between them a mandrel 15, which, as shown, consists of an upper sector-shaped flat portion 16, at the upper and wider end of which is mounted on each side a pair of small idlers 17, 18, preferably having convex faces for engaging in the grooves of the pulleys 14. It will be seen that the width of the portion 16 at its upper end is such that the idlers 17 and 18 engage respectively above and below the horizontal diameter of the pulleys 14, so that the mandrel 15 is thereby supported and prevented from vertical movement in either direction, as well as from lateral movement. Extending laterally from, and in the present instance at a right angle with, the portion 16 are triangular blades 19, the lower ends 20 of which are united and are together of a width approximately equal to that of the upper end of the part 16. Mounted on shafts 21 below the shafts 13 are two large rolls 22, 23, one of the shafts 21 being connected with a source of power, not shown, for rotating the same. On the roll 22 is a sprocket wheel 24 connected by a sprocket chain 25 to a similar sprocket wheel 26 on a small shaft 27 supported on a suitable standard 28 on the frame of the machine. The shaft 27 carries a spur wheel 29 meshing with a similar spur wheel 30 on the shaft 21 of the roll 23. It is obvious that the effect of this mechanism is to cause the rolls to be simultaneously and equally rotated with their adjacent faces moving in the same direction, in the present instance, downward, as shown by the arrows in Fig. 3. It will also be seen

that the lower end 20 of the mandrel 15 extends downwardly somewhat between the rolls 22 and 23 and parallel with the axis thereof. On the roll 23 is shown a plurality of blades 31, 32, of broken contour, and in the present instance adapted to cut from the tubular web 33 shirt bodies 34, such as are shown in Fig. 2 of the drawings. The blades 31 and 32 are adapted to coöperate with a stationary blade 35, which is suitably secured in a bracket or standard 36 mounted on the frame of the machine. The roll 22 is provided with recesses 37, 38 adapted to receive the blades 31, 32 respectively. The faces of the rolls 22 and 23 are, in the present instance, formed with diagonally disposed lines. These are preferably produced by securing on the faces of the roll sheets of rubber cloth 39 or the like having these diagonal lines 40 formed therein. A reference to Fig. 4 of the drawings will clearly show that these lines are so disposed as to maintain the lateral tension on a web passing between the rolls and preferably to slightly stretch it laterally, that is, to increase such lateral tension.

The operation of the device is as follows: The end of a tubular web 33, which it is desired to cut into pieces, usually of broken contour, and in the present instance into shirt bodies, is slipped over the upper end of the mandrel 15, so that it passes between the idlers 17 and 18 and the grooved pulleys 14. It is understood that in this position the selvages 41 of the web are at the edges of its faces 42, that is, the web is in its natural folds. The web is then drawn down over the mandrel 15, by which it is folded to bring its selvages 41 into superposition or together, forming new folds in the middle of each face 42 of the web. The web thus folded is passed between the rollers 22 and 23, which act to press together the faces of the web in their folded position, and to maintain or slightly increase its lateral tension. The machine being started, it is evident that the web will be continuously fed over the mandrel 15, will be folded to bring its selvages on the faces of the web, and in the present instance in superposition, and that the blades 31 and 32 on the roll 23 in coöperation with the blade 35 will act to cut simultaneously through both plies of the web, and form, in the present instance, the shirt bodies shown in Fig. 2 of the drawings, it being understood that the blades 31 are adapted to cut the shoulder seam and arm scye portion at the upper portion of the shirt body, and the blade 32 adapted to cut the lower end of the skirt of the shirt, rounding off its corners as shown.

By referring to Fig. 1 of the drawings, it will be seen that the tubular article after same has been cut from the tubular web, as shown in Fig. 2, can readily be refolded so

as to bring the back and front of the shirt body in superposed relation and the tubular article will then be ready for the sewing or finishing operation. By folding the web as in the present device, both plies are cut simultaneously and exactly alike, so that the tubular article when refolded to its original folds, will present the appearance shown in Fig. 1. In both these drawings the fronts of the shirts are designated by the numerals 43, and the backs by the numerals 44.

In the form of mandrel shown in Fig. 7, the blades 19 are replaced by bars 50, each of which is pivoted at its upper end 51 and is guided to move at a right angle with the sector 16 between a pair of brackets 52. Near the lower end of each of the bars 50 is a spring 53, by which it is forced laterally outward from the portion 16. It is obvious that the lower corners 54 of the bars will act to fold the web just as the blade 20 does in the form of device shown in Fig. 6, and that the operation of the device will not be changed by this alteration, except that the lateral tension on the web will be somewhat increased.

Figs. 8, 9 and 10 of the drawings show a preferred form of my folding and cutting device, in which the mandrel is dispensed with. The bed 11 and uprights 12 will be as before described. Mounted on a pair of cross bars 61 are bearings 62, in which rotate shafts 63, 64, on each of which is mounted a roll 65, 66. Guides 67, shown as bent rods, may be provided above the adjacent faces of the rolls 65, 66 for laterally guiding the web between them. Mounted in cross bars 68 of the frame below the cross bars 61 are shafts 69, 70, each of which carries a roll 71, 72 respectively, these being similar to the rolls 22 and 23 shown in the form of device first described. As a means of rotating the rolls 71, 72 I provide a short shaft 73 mounted on a standard 74 on the bed of the machine, on which is a bevel gear 75 meshing with a similar bevel gear 76 on the shaft 69. A sprocket wheel 77 also mounted on the shaft 69 carries a sprocket chain 78, which passes over a similar sprocket wheel 79 mounted on a short shaft 80 supported on a standard 81. The shaft 80 also carries a spur wheel 82, which meshes with a corresponding spur wheel 83 on the shaft 70. It will be understood that the arrangement of parts is such that the rolls 71, 72 are simultaneously and equally rotated in opposite directions with their adjacent faces traveling in the same direction, in the present instance, downward, as shown by the arrows in Fig. 8. It is sometimes preferable to rotate the upper rolls 65 and 66 in like manner, and for this purpose I provide on the shaft 73 a pulley 84, which is connected by a belt 85 with a pulley 86 on the shaft 64. Suitable spur pinions 87 and 88 on the

shafts 63 and 64 respectively act to rotate the rolls 65, 66, as before described. It is understood that the rolls 71, 72 are preferably faced, as before, with sheets of rubber 5 cloth 39 having diagonal lines 40 formed therein, these lines being disposed, as already described with reference to Fig. 4 of the drawings. One of the rolls, as 72, also carries cutting blades 89, the other roll, as 71, 10 being formed with recesses 90 for receiving the same. For convenience of illustration, I have shown the blades 89 as adapted to cut the shirt bodies shown in Fig. 2 of the drawings. As an additional means of folding 15 and creasing the new folds in the web 33 to be cut, I provide adjacent each end of the rolls 71, 72 a pair of small idler rolls 91, the axes of which are in a plane approximately at a right angle with the edges of the web as 20 these are fed between the rolls 71 and 72. In the present instance I have shown these small rolls 91 mounted on brackets 92 on a cross bar 93 suitably supported in the frame of the machine. The operation of this form 25 of the device will be readily understood from an inspection of the drawings. Fig. 8 shows the web 33 as being fed between the rolls 65 and 66, its selvages 41 being in their normal position at the edges of the web. 30 After the web passes between these rolls the middle line of each face is creased and passed first between the idler rollers 91 and then between the large rolls 71 and 72. It will be seen that in the present instance the 35 axes of these rolls 71 and 72 are at a right angle with the axes of the rolls 65 and 66, so that the cloth will be folded with its original selvages superposed one upon the other. The cutting operation is similar to 40 that already described, the blades 89 coöperating with a blade 35 mounted on a bracket 36. It is desirable that the blades 89 and 35 should not come in exact contact with each other so as to wear, and I prefer to set 45 them about one-thousandth of an inch apart, which effectually cuts the web passing between them, while preventing any undue wear upon the blades. For this purpose I have shown in Fig. 10 the blade 35 as provided with slots 94, so that it may be vertically adjusted and held in position by bolts 50 secured in the standard 36. 55 It is obvious that many mechanical changes may be made in my device without departing from the spirit of the invention 60 as set forth in the claims. Thus, *e. g.*, the vertical arrangement of the machine shown is obviously a matter of convenience. When, therefore, I speak of the cutting rolls as 65 being below or beneath the mandrel or the upper rolls between which the web is engaged, it is obvious that I intend to include any position of these rolls in which they are adapted to receive the web and to re-fold 70 and cut the same.

What I claim is:

1. A web cutting machine comprising continuously operating means for feeding forward a tubular web, for folding the web to bring its selvages on the faces thereof and 70 for cutting the web.

2. A web cutting machine comprising continuously operating means for feeding forward a tubular web, for folding the web to superpose its selvages and for cutting the 75 web.

3. A web cutting machine comprising continuously operating means for feeding forward a tubular web, for folding the web to bring its selvages on the faces thereof and 80 for cutting both plies of the web simultaneously.

4. A web cutting machine comprising continuously operating means for feeding forward a tubular web, for folding the web to 85 superpose its selvages and for cutting both plies of the web simultaneously.

5. A web cutting machine comprising continuously operating means for feeding forward a tubular web, for folding the web 90 to bring its selvages on the faces thereof, for maintaining lateral tension on the folded web, and for cutting the web.

6. A web cutting machine comprising continuously operating means for feeding forward a tubular web, for folding the web to 95 superpose its selvages, for maintaining lateral tension on the folded web, and for cutting the web.

7. A web cutting machine comprising continuously operating means for feeding forward a tubular web, for folding the web to bring its selvages on the faces thereof, for maintaining lateral tension on the folded web, and for cutting both plies of the web 105 simultaneously.

8. A web cutting machine comprising continuously operating means for feeding forward a tubular web, for folding the web to superpose its selvages, for maintaining lateral tension on the folded web, and for cutting 110 both plies of the web simultaneously.

9. A web cutting machine comprising means for folding a tubular web to bring its selvages on the faces of the web, and 115 means for cutting the folded web into pieces of broken symmetrical contour.

10. A web cutting machine comprising means for folding a tubular web to superpose its selvages, and means for cutting the 120 folded web into pieces of broken symmetrical contour.

11. A web cutting machine comprising means for folding a tubular web to bring its selvages on the faces of the web, and 125 means for cutting both plies of the folded web simultaneously into pieces of broken symmetrical contour.

12. In a web cutting machine, the combination of means for folding a tubular web 130

- to superpose its selvages, with means for cutting both plies of the web simultaneously into pieces of broken symmetrical contour.
13. A web cutting machine comprising continuously operating means for feeding forward a tubular web, for folding the web to bring its selvages on the faces thereof and for cutting the folded web into pieces of broken symmetrical contour.
14. A web cutting machine comprising continuously operating means for feeding forward a tubular web, for folding the web to superpose its selvages and for cutting the folded web into pieces of broken symmetrical contour.
15. A web cutting machine comprising continuously operating means for feeding forward a tubular web, for folding the web to superpose its selvages and for cutting both plies of the folded web simultaneously into pieces of broken symmetrical contour.
16. A web cutting machine comprising means for folding a tubular web to superpose its selvages, and means for cutting both plies of the folded web simultaneously into tubular pieces having symmetrical contours on opposite original faces of the web.
17. A web cutting machine comprising means for folding a tubular web to superpose its selvages, and means for cutting both plies of the folded web simultaneously into tubular pieces having different symmetrical contours on opposite original faces of the web.
18. A web cutting machine comprising continuously operating means for feeding forward a tubular web, for folding the web to superpose its selvages and for cutting both plies of the folded web simultaneously into tubular pieces having symmetrical contours on opposite original faces of the web.
19. A web cutting machine comprising continuously operating means for feeding forward a tubular web, for folding the web to superpose its selvages and for cutting both plies of the folded web simultaneously into tubular pieces having different symmetrical contours on opposite original faces of the web.
20. In a web cutting machine means for folding a tubular web to bring its selvages on the faces of the web, said folding means including a pair of rolls for pressing together the faces of the web in their folded position, the surfaces of said rolls being constructed and fitted to increase the lateral tension of the folded web, and means for cutting the web after same has been folded.
21. A web cutting machine comprising continuously operating means for feeding forward a tubular web, for folding the web to bring its selvages on the faces thereof and for cutting the web, said means including a pair of coöperating rolls for pressing together the plies of the web in their folded position, the surfaces of said rolls being constructed and fitted to increase the lateral tension of the web and the cutting blade on one of said rolls.
22. A web cutting machine comprising continuously operating means for feeding forward a tubular web, for folding the web to bring its selvages on the faces thereof and for cutting the web, said means including a pair of coöperating rolls for pressing together the plies of the web in their folded position and a cutting blade of broken contour on one of said rolls, and a blade mounted on the frame of the machine for coöperation with said roll blade.
23. A web cutting machine comprising continuously operating means for feeding forward a tubular web, for folding the web to bring its selvages on the faces thereof and for cutting the web, said means including a pair of coöperating rolls for pressing together the plies of the web in their folded position and a cutting blade of broken contour on one of said rolls, and a blade mounted on the frame of the machine for coöperation with said roll blade, one of said blades being adjustable.
24. A web cutting machine comprising continuously operating means for feeding forward a tubular web, for folding the web to bring its selvages on the faces thereof and for cutting the web, said means including a pair of coöperating rolls for pressing together the plies of the web in their folded position and a cutting blade of broken contour on one of said rolls, and an adjustable blade mounted on the frame of the machine for coöperation with said roll blade.
25. A web cutting machine comprising two parallel adjacent parts for engaging the opposite faces of a tubular web, a pair of rolls located beneath said parts with their axes at an angle therewith, means for positively rotating said rolls with their adjacent faces moving in the same direction, whereby a tubular web passing between them may be folded with its selvages on the faces of the web, and means for cutting the web.
26. A web cutting machine comprising two parallel adjacent parts for engaging the opposite faces of a tubular web, a pair of rolls located beneath said parts with their axes at a right angle therewith, means for positively rotating said rolls with their adjacent faces moving in the same direction, whereby a tubular web passing between them may be folded with its selvage superposed, and means for cutting the web.
27. A web cutting machine comprising two parallel adjacent parts for engaging the opposite faces of a tubular web, a pair of rolls located beneath said parts and at an angle therewith, means for positively rotating said rolls with their adjacent faces

moving in the same direction, whereby a tubular web passing between them may be folded with its selvages on the faces of the web, and means for cutting both plies of the web simultaneously.

28. A web cutting machine comprising two parallel adjacent parts for engaging the opposite faces of a tubular web, a pair of rolls located beneath said parts and at an angle therewith, means for positively rotating said rolls with their adjacent faces moving in the same direction, whereby a tubular web passing between them may be folded with its selvages on the faces of the web, and means including a blade on one of said rolls for cutting the web.

29. A web cutting machine comprising a pair of rolls for engaging the opposite faces of a tubular web, a second pair of rolls located beneath said first-named rolls with their axes at an angle therewith, means for positively rotating both said pairs of rolls with the adjacent faces of each pair moving in the same direction, whereby a tubular web passing between them may be folded, and means for cutting the web.

30. A web cutting machine comprising a pair of rolls for engaging the opposite faces of a tubular web, means located adjacent said rolls for guiding the web therebetween, a second pair of rolls located beneath said first-named rolls with their axes at an angle therewith, means for positively rotating both said pairs of rolls with the adjacent faces of each pair moving in the same direction, whereby a tubular web passing between them may be folded, and means for cutting the web.

31. A web cutting machine comprising a pair of rolls for engaging the opposite faces of a tubular web, a second pair of rolls located beneath said first-named rolls with their axes at an angle therewith, means for positively rotating both said pairs of rolls with the adjacent faces of each pair moving in the same direction, means located adjacent said last-named rolls for creasing new folds in the web, whereby a tubular web passing between them may be folded, and means for cutting the web.

32. A web cutting machine comprising a pair of rolls for engaging the opposite faces of a tubular web, a second pair of rolls located beneath said first-named rolls with their axes at an angle therewith, means for positively rotating both said pairs of rolls with the adjacent faces of each pair moving in the same direction, a pair of small rollers located adjacent each end of said last-named rolls for creasing new folds in the web, whereby a tubular web passing between them may be folded, and means for cutting the web.

33. In a web cutting machine, a pair of rolls for engaging the opposite faces of the

web, means for rotating said rolls with their adjacent faces moving in the same direction, a cutting blade on one of said rolls, a recess in the other roll for receiving said blade, and a second blade mounted independently of said rolls for coöperating with said first-named blade.

34. In a web cutting machine, a pair of rolls for engaging the opposite faces of the web, means for rotating said rolls with their adjacent faces moving in the same direction, a cutting blade on one of said rolls, a recess in the other roll for receiving said blade, and a second blade adjustably mounted independently of said rolls for coöperating with said first-named blade.

35. In a web cutting machine, a pair of rolls for engaging the opposite faces of the web, means for rotating said rolls with their adjacent faces moving in the same direction, means on said rolls for maintaining lateral tension on the web, a cutting blade on one of said rolls, a recess on the other roll for receiving said blade, and a second blade mounted independently of said rolls for co-90 operating with said first-named blade.

36. A web cutting machine comprising a pair of rolls having their surfaces constructed and fitted to feed forward a web passing between them and to maintain lateral tension on the web, and means including a cutting blade mounted on one of said rolls for cutting the web.

37. A web cutting machine comprising a pair of rolls having their surfaces constructed and fitted to feed forward a web passing between them and to maintain lateral tension on the web, and means including a cutting blade mounted on one of said rolls and a blade fixed on a stationary portion of the machine coöperating therewith for cutting the web.

38. A web cutting machine comprising a pair of rolls constructed and fitted to feed forward a web passing between them and to maintain lateral tension on the web, and means including a cutting blade mounted on one of said rolls and a blade adjustably secured on a stationary portion of the machine coöperating therewith for cutting the web.

39. In a web cutting machine, a pair of rolls provided one with a cutting blade, the other with a recess for receiving said blade, and constructed and fitted to feed forward a web passing between them, at least one of said rolls being provided with means for maintaining lateral tension on the web.

40. In a web cutting machine, a pair of rolls provided one with a cutting blade, the other with a recess for receiving said blade, and constructed and fitted to feed forward a web passing between them, both of said rolls being provided with means for maintaining lateral tension on the web.

41. In a web cutting machine, a pair of

rolls provided one with a cutting blade, the other with a recess for receiving said blade, and constructed and fitted to feed forward a web passing between them, the face of at least one of said rolls being formed with oppositely diagonally disposed ribs for maintaining lateral tension on the web.

42. In a web cutting machine, a pair of rolls provided one with a cutting blade, the other with a recess for receiving said blade, and constructed and fitted to feed forward

a web passing between them, the faces of both of said rolls being formed with oppositely diagonally disposed ribs for maintaining lateral tension on the web. 15

In testimony whereof I have signed this specification in the presence of two subscribing witnesses.

ARTHUR JAMES CUMNOCK.
